(57) **CLAIM**

We claim the ornamental design for a tabletop remote load control device, as shown and described.

DESCRIPTION

FIG. 1 is a perspective view of a tabletop remote load control device according to our new design.

FIG. 2 is a top view thereof.

FIG. 3 is a left side view thereof.

FIG. 4 is a right side view thereof.

FIG. 5 is a front view thereof.

FIG. 6 is a rear view thereof.

FIG. 7 is a bottom view thereof.

FIG. 8 is an alternate view thereof taken in a direction that is normal to the front surface of the angled portion of the tabletop remote load control device; and,

FIGS. 9-14 are enlarged views of the buttons of the tabletop remote load control taken in a direction that is normal to the front surface of the angled portion.

(Continued)

The broken lines showing portions of the tabletop remote load control device are for the purpose of illustrating environmental structure and form no part of the claimed design.

1 Claim, 10 Drawing Sheets
